UNITED STATES PATENT OFFICE.

CHARLES E. WAREAM, OF CINCINNATI, OHIO, ASSIGNOR TO THE AMERICAN LAUNDRY MACHINERY COMPANY, OF CINCINNATI, OHIO, A CORPORATION OF OHIO.

IRONING MACHINE.

Application filed August 5, 1921. Serial No. 490,100.

This invention relates to ironing machine and more especially to that class of ironing machines used in ironing small flat articles on one side of which it may be desirable to produce a highly finished or polished surface, such as collars and cuffs.

This application is a continuation in part of my co-pending application, Serial No. 427,767, filed December 2, 1920.

10 As in my co-pending application just referred to, the objects of the present invention are to provide an improved ironing machine in which small articles may be ironed in a flat form; to provide means for preliminarily ironing the articles before being thoroughly dried by the main chest portion of the machine; to provide an improved relative arrangement of padded rolls and ironing chest in which the rolls and chest 15 have relative reciprocatory motion in the direction of travel of the articles between them, and more specifically in which the chest reciprocates, for the purpose of avoiding deposits of starch and rust on the ironing portion of the chest; to simplify and improve the arrangement of the driving means for the rolls so as to maintain said gears in true meshing relation and at the same time permit the rolls to be raised from the chest 20 to avoid burning or injuring of the padding; to provide an improved ironing machine which is capable of producing a highly finished or burnished effect upon the inner surface of the band and the outer surface 25 of the flap; to simplify and improve the manner of applying and removing the padding from the padded rolls; to provide a simpler arrangement for raising the padded rolls from the chest and producing relative 30 movement of the padded and ironing or polishing rollers; to provide a battery of rollers which increase in diameter in the direction of travel of the work so as to produce a stretching of the work and thereby 35 maintain the same in flat condition; to provide means for varying the pressure of the rollers upon the chest; to provide means for indicating the raised and lowered positions 40 of the rollers with respect to the chest; to provide improved steam connections to the heating rolls and the chest so as to permit proper movement of the same; to provide means for preventing the work from sticking to the rolls and also an improved means of 45 applying and removing such means; and to 50

provide a convenient means for replacing the covering on the padded rolls.

Other objects of the present invention will appear from the following description and claims when considered together with the 60 accompanying drawings.

Fig. 1 is a vertical longitudinal section of the ironing machine through line 1—1, Fig. 5; Fig. 2 is a vertical longitudinal section through line 2—2, Figs. 5 and 11; Fig. 3 is a vertical longitudinal section through line 3—3, Figs. 5 and 11; Fig. 4 is an elevation of the right hand side of the machine; Fig. 5 is a plan view of the machine; Fig. 6 is a vertical longitudinal section through line 6—6, Figs. 5, 9 and 11; Fig. 7 is a vertical longitudinal section of one of the steam joints which supply steam to the hot rolls taken on line 7—7, Figs. 1, 2 and 5; Fig. 8 is a vertical longitudinal section of one of the swivel joints taken on line 8—8, Fig. 6; Fig. 9 is a horizontal section taken on line 9—9, Figs. 1, 2, 3, 4 and 6; Fig. 10 is a vertical longitudinal section of the rear portion of the machine on line 10—10, Figs. 5 and 9; Fig. 11 is a vertical transverse section on line 11—11, Fig. 5; Fig. 12 is a vertical longitudinal section of the front portion of the machine on line 12—12, Figs. 5 and 9; Fig. 13 is a horizontal section on line 13—13, Figs. 1, 2, 3 and 6 showing the lever mechanism for the fourth padded roll; Fig. 14 is a vertical transverse section on line 14—14, Figs. 1, 2 and 3; Fig. 15 is a vertical transverse section of one of the pressure eccentrics on line 15—15, Figs. 1, 2, 3, 6 and 9; Fig. 16 is a vertical longitudinal section on line 16—16, Fig. 5; Fig. 17 is a vertical longitudinal section on line 17—17 of Figs. 5 and 11 showing the driving mechanism for the first four padded rolls and first four heated rolls; Fig. 18 is a vertical longitudinal section on line 18—18, Figs. 5 and 11 showing a portion of the roll driving mechanism; Fig. 19 is a section on line 19—19, Figs. 4, 5, 17 and 18; Fig. 20 is a plan view of a portion of the front rolls showing the arrangement of the doffer knives; Fig. 21 is a plan view of a portion of one of the first padded rolls, a part of the pressure bar being broken away to show the interior construction; Fig. 22 is a vertical section on line 22—22, Figs. 1, 2 and 5 showing the pressure indicator; Fig. 23 shows a tool used to hold the doffer 110

knives in place and to remove the same, and Figs. 24 and 25 are detail sectional views on the lines 24-24 and 25-25, Fig. 20, respectively.

5 Briefly stated my improved machine comprises preliminary sets of padded pressure or feeding rolls and heated ironing rolls oppositely arranged with respect to each other and between which the work is fed before reaching a second battery or gang of padded pressure or feeding rolls which rotate above a reciprocating steam heated ironing chest. When it is desired to give a polish to the work, the preliminary heated 10 rolls which have a metallic ironing surface are rotated at a greater rate of speed than the co-operating padded rolls, although all of the preliminary rolls may be rotated at the same rate of speed when a dull finish is 15 desired. The function of the second battery of rolls and steam heated chest is to thoroughly dry the work and to set the gloss or polish on the materials. The reciprocation of the chest furthermore prevents accumulation 20 of starch and rust and thereby preserves the ironing surface of the chest in proper operative condition. After passing the second gang of rollers and the chest, the work 25 is delivered out through the end of the machine.

The side frames 1 and 2 of the supporting structure are braced by suitable rods 3 and suitable brackets are provided also for support of the gears and other parts of the 30 mechanism to be described. The table 4 is provided at the one end of the machine while the container 5 is provided for receiving the work at the other end. The preliminary heated rolls 6, 7 and 8 are rotatably 35 mounted in the frame while the preliminary padded rolls 9, 10 and 11 are mounted thereabove for rotation and are supported from the pressure bars 12 which may be raised and lowered with respect to the rest of the 40 machine. Two such pressure bars are arranged along the sides of the machine. The padded rolls comprising the second battery are indicated at 13 and are also supported by the pressure bars so as to be raised 45 and lowered with respect to the chest 14 which extends therebelow. The rolls 13, as clearly indicated in Fig. 6, increase in 50 diameter in the direction of the travel of the work through the machine so that the peripheral speed of each roll is slightly greater than that of the preceding roll so as to stretch the work and maintain and deliver the same in flattened condition. The axes 55 of these rolls may or may not be equi-distant from each other. The chest 14 is suitably mounted for reciprocating movement upon the rollers 15 which are engaged by the flanges 16 on the bottom of the chest and also by the upstanding flanges 17 of 60 the angle irons which extend along the

inwardly extending flanges 18 provided on the top portions of the frame members 1 and 2. The padded rolls 9, 10 and 11 are supported from the pressure bars by means of the hangers 20 suspended from the flanges 21 provided on the pressure bars, the hangers 20 at their other ends receiving the pins 22 extending through ears 23 provided upon the bearings of the padded rolls. The springs 24 are also provided within the pressure bars and bear against the bearings of the padded rolls for the purpose of individually regulating the pressure of the padded rolls against the heated rolls when in lowered or operative position. Such regulation of the tension of these springs is effected by means of screws 25. When in lowered position the pressure bars are free of the weight of the rolls.

The driving mechanism for the padded rolls 9, 10 and 11 will now be described. Any suitable source of power may be employed for driving the present machine and in the present illustration I have shown a drive pulley 30 provided with a clutch mechanism 31 under control of the lever 32 which has connection through rod 33, bell crank lever 34, rod 35, bell crank lever 36 to operating lever 37 which is pivoted on the bracket 38. Thus upon operation of this clutch control mechanism, the shaft 40 can be set in operation and consequently the shaft 41 on the other side of the machine through the bevel gears 42 and 43. The bevel gear 44 carried by the shaft 41 meshes with bevel gear 45 on the stub shaft on which is mounted the pinion 46. Referring now to Fig. 4, the first padded roll 9 is operated through the meshing pinions and gears 46, 47, 48, 49, 60, 60^a, 60^b and 53, the last gear being on the shaft of the padded roll. The third padded roll 11 receives its operation through the meshing gears and pinions, 46, 47, 48, 54, 55, 56, 57, 58 and 59, the last gear 59 being one of the compound gears on the shaft of roll 11. The other gear of this compound gear drives the second padded roll 10 through gear 59^a. These gears are arranged in mesh so that the drive for the padded rolls 9, 10 and 11 is through a continuous chain of gears. These rolls are driven in clock-wise direction.

The heated roll 6 receives its operation from the pinion 46 through the meshing gears 47, 48, 49, and 60, the gear 60 being on the shaft of the heated roll 6. The second heated roll 7 receives its operation from the pinion 46 through the meshing gears 47, 48, 49 and 50, the gear 50 being on the shaft of the roll 7. The third heated roll 8 receives its operation from the gear 46, through the meshing gears 54 and 61, the gear 61 being mounted upon the shaft of the roll 8. These heated rolls are driven in counter-clockwise direction, Fig. 6.

Another heated roll 62 is rotatably mounted in the frame of the machine and is driven clock-wise, Fig. 6, from the pinion 46 through the meshing gears 54, 55 and 56, the gear 56 being mounted upon the shaft of the roll 62. As will be seen from the drawings, this heated roll is mounted in substantially horizontal alignment with padded rolls 9, 10 and 11. The fourth padded roll 63, which is mounted in substantially horizontal alignment with heated rolls 6, 7 and 8, is driven counter-clockwise, Fig. 6, from one of gears 74 through gears 74^a and 63^a, the last named gear being on the shaft of roll 63. The finger guard 37^a is connected to the clutch operating lever 37 so that should the operator try to insert his hand beyond this point in feeding the work, the guard 37^a will be actuated and consequently the driving clutch of the machine will be thrown out.

Tumbler links 53^a are provided between the shafts of the rolls and the stub shafts of the gears, as clearly illustrated in Figs. 17 and 18, and likewise link 62^a between the shaft of heated roll 62 and the shaft of gear 57. Link 60^c connects the studs of gears 60^a and 60^b, while link 53^b is provided between the stub of gear 60^b and the shaft of padded roll 9. Due to the tumbler arrangement of the gears, the raising of the pressure bars and the rolls will not disturb the mesh of the gears.

The mechanism for operation of the second battery of padded rolls will now be described. The shaft 40 carries the worm gear 65 which meshes with gear 66 on the shaft 67. Fixed upon the shaft 67 are the bevel gears 68 and 69 which mesh with the beveled gears 70 and 70^a, respectively. Carried by the stub shafts of the bevel gears, 70 and 70^a are pinions 71 and 72, respectively, each of which meshes with a pair of gears 73 and 74. As indicated in Fig. 2, each of the gears 73 and 74 meshes with a pair of gears 75 mounted on the shafts of the padded rolls 13 for rotation thereof. The pressure rolls 13 are supported by means of the hangers 76 suspended from the pressure bars and connected at their lower ends to the ears provided on the pressure member 77 which in turn support the shafts of the padded rolls. The depending arms 78 of the pressure members support the shafts of the driving gears 73 and the links 80 are provided between the shafts of the gears 73 and 71 whereby it is possible for the pressure members to be raised and lowered with the pressure bar and always preserve meshing relation between the gears. The degree of pressure of the padded rolls 13 with respect to the chest can be regulated individually by means of the springs 81 and the adjusting screws 82 therefor. The pressure arm 85 is connected at one end to the

stud shaft of gear 74 and is provided with a bearing for sliding bearing 86, which is fitted to slide in recess 90 in the frame. The outer end of arm 85 has a cup 86^a to receive pressure spring 87 for the padded roll 63. The links 88 connect the sliding bearing 86 to the shaft of the padded roll 63, and a pin 88^a engaging a hole in pressure arm 85 connects the two links. Thus the padded roll 63 is adapted for movement away from its heated roll upon raising the gang of padded rolls away from the chest.

The mechanism for raising and lowering the pressure bars will now be described. Fast upon the shaft 40 is the pinion 91 meshing with the gear 92 on the shaft 93 upon which is splined the clutch member 94 for clutching engagement with the loosely mounted bevel gear 95. The clutch 94 is controlled by means of the lever arm 96, the outer end of which is guided by means of strap 97. Upon throwing in clutch 94, the bevel gear 95^a drives the shaft 97 and also the worm gears 98 and 99 carried thereby. The worms 98 and 99 drive the gears 100 and 101, respectively. These gears are fixed upon the eccentric shafts 102 and 103, respectively, the eccentrics working in the straps 104 and 105, respectively, carried by the lower ends of the operating rods 106 and 107, respectively. These rods are connected at their other ends to the pressure bars so as to raise and lower the same upon operation of the driving mechanism just now described. That is, when it is desired to raise the pressure bars, the clutch 94 is thrown in and when the pressure bars have been brought to the desired elevation the clutch will be thrown out. The pressure bars can be raised to the height desired corresponding to 180° or less rotation of the eccentric. Means are also provided whereby the pressure bars may be raised by manual operation of the hand wheel 110 which is mounted upon shaft 97 for manual operation of the worms 98 and 99 and the other mechanism controlled thereby. The pressure bars can likewise be lowered to the proper degree according to the degree of pressure desired for the rolls.

The mechanism for reciprocating the steam chest will now be described. Fixed upon the shaft 67 is the worm 115 which meshes with the gear 116 fixed upon the shaft 117, carrying gear 118 which in turn meshes with gear 119 on shaft 120. The gear 121 fixed on shaft 120 meshes with gear 121^a fixed on shaft 122. The crank arms 123, fixed upon the shaft 122 at the two ends thereof, have pivotal connection with the rods 124 which are connected at their other ends to the depending brackets 125 on the under face of the steam chest. Thus it will be seen that when the machine is set in operation, the steam chest will be given a recip-

rotatory motion which is designed to be comparatively slow with reference to the speed of the rolls thereabove and of sufficient extent to bring all portions of the ironing surface of the chest in contact with the padded rollers thereabove. The chest will move a distance equal at least to that between the axes of the most widely spaced adjacent rolls. A felt wiper 126 is suitably mounted in the frame 126^a secured to the under side of one of the doffer knives 160^a Fig. 16, so as to have wiping contact with the rear portion 127 of the chest which does not contact with the rollers, so as to prevent accumulation of starch or rust. A guide 167 is secured over this doffer knife for guiding the work and this doffer knife is secured in place in generally the same manner as the other doffer knives 160. The doffer knives prevent the work from sticking to the rolls and will be referred to again.

The heated rolls 6, 7, 8 and 62, as best illustrated in Fig. 7, receive steam for heating the same through the inlet pipe 128 and are provided with a syphon outlet 129 so arranged as to discharge any condensed steam under pressure of the incoming live steam. As indicated in Fig. 7, the steam pipe connections extend through the gudgeon 131 and a suitable stuffing box 132 so as to permit the heated rolls to rotate in the manner described without disturbing the stationary steam pipe connections therefor.

The steam connections for the steam chest are best illustrated in Figs. 6, 8 and 11. Steam enters through pipe 135 into chamber 136 of the joint 135', which is suitably supported on one of the brace rods 3, and out through pipe 137 whence it is delivered through a similar joint 138, thence to pipe 139, through another like joint 140, whence the steam enters the chest through the pipe connection 141. Upon leaving the chest, the steam passes through pipe 142, through the other side of joint 140, thence out through pipe 143, through the other side of joint 138 and finally through pipe 135' to the other side of the first joint, through chamber 136' whence it passes through pipe 137' to the exhaust. As indicated in the drawings, these steam joints are so constructed as to permit the reciprocatory motion of the chest without disturbing the steam connections. This is made possible by the swivel connections at the joints and suitable packing means provided at these points.

In order to indicate to the operator whether the pressure bars are in raised or lowered position, that is whether the padded rolls carried thereby are "off" or "on" with respect to the steam chest, I have provided an indicating means automatically operated by movement of the pressure bars. The indicating dial 150 bearing the marks

"Off" and "On" is fixedly mounted on one of the pressure bars as indicated at 152. Upon the frame of the machine I have provided the fixed bracket 153 to which is pivoted the clevis 154 threaded on the upwardly extending rod 155. The other end of rod 155 is threaded in the clevis 156 which has pivotal connection at 157 with the link 157^a connected to the indicating finger 158. Finger 158 is pivoted on the dial so as to move over the face of the dial upon raising and lowering the pressure bar and to indicate the degree to which the pressure bars have been raised or lowered with respect to the steam chest.

The doffer knives 160, 160^a, above referred to, prevent the work from sticking to the rolls and being carried around with them. These knives (Fig. 24) are metal plates supported upon brackets 161, 161^a secured to the stationary frame. Each knife 160 is held in place by applying the threaded socket 162^a of a tool 162, Fig. 23, to each of the two bolts 163 extending up through the opposite ends of the doffer knife from its supporting brackets 161, the tools thereby serving as clamping nuts for the knife. To remove said knife, the tools are unscrewed from its bolts and their handle ends 164 are inserted through or into the elongated openings 164^a of bails or bridges 165, one on each end of the doffer knife, to remove it by lifting it from its bolt. Doffer knife 160^a differs slightly from knives 160, as shown in Fig. 25, its guiding plate 167 having end flanges through which the securing bolts 163 pass and separate slots 164^b in its body for reception of the handle end of the tools 162 for removing it. The guide 167 and bridges 165, of course, are solidly secured in unitary form with their respective doffer knives.

With my device it is also possible to remove the padding from the padded rolls whenever necessary and to replace the same by utilizing the power of the machine. This is accomplished by loosening the outside end of the padding which is preferably muslin or the like, and upon disengaging the individual clutch 170 of the particular roll, the padding material can be unwound from the roll which is then free to rotate independently of its driving connection. Then upon replacing the old padding with the new material, the one end of the material is suitably attached to the core of the roll and the individual clutch is then thrown in and the power turned on so as to wind the new material on to the roll to the extent desired. The machine is then stopped and the outer end of the padding may be secured in any suitable manner, it being preferable however, to depend upon cohesion of the material for securing the same to prevent any wrinkling of the padding.

which might result should the outer end be positively fastened. For this purpose, each padded roll is provided with such a clutch 170 for throwing the roll into and out of driving connection with the driving gear freely mounted upon the shaft of the roll.

The operation is briefly stated as follows. When ironing a collar for instance, it is laid flat with the outer face of the flap and 10 the inner face of the band down so as to engage the preliminary heated rolls as it is fed into the machine. The relatively great speed of the heated rolls gives a polish or gloss to the faces exposed thereto. As the 15 collar then passes between the rolls 62 and 63, the inner face of the flap and the outer face of the band are ironed as they pass over the metallic ironing surface of the heated roll 63. Thus the collar which has 20 now been ironed and polished is fed between the ironing chest and padded rolls to be thoroughly dried and to have the polish set. For a domestic finish, the operation is 25 the same except that all the rolls are driven at the same speed so as to omit the polish.

Heretofore, the inner face of the flap of a collar has been ironed first and the gloss given to its outer face later, that is after the collar has become practically dry. With 30 my machine, however, the polish is given to the outer face of the flap before being thoroughly dried and consequently better results are obtained.

Other advantages flowing from this invention will be apparent to those who are 35 familiar with the art to which it relates.

What I claim is:—

1. A collar ironing machine, comprising preliminary polishing means including an initial set of lower ironing and upper pressure rolls and an intermediate set of rolls, drying means including a heated chest and a gang of upper feeding pressure rolls cooperating therewith and receiving the collars from said polishing means, and movable pressure bar members supporting said gang of pressure rolls and extending beyond said intermediate preliminary rolls and supporting the pressure rolls of said initial set.
2. A collar ironing machine, comprising preliminary polishing means including an initial set of lower ironing and upper pressure rolls and an intermediate set of rolls, drying means including a heated chest and a gang of upper feeding pressure rolls cooperating therewith and receiving the collars from said polishing means, movable pressure bar members supporting said gang of pressure rolls and extending beyond said intermediate preliminary rolls and supporting the pressure rolls of said initial set, said chest having an end extension and being reciprocable longitudinally of the machine, and a doffer knife located between said intermediate rolls and chest for stripping the work from the intermediate rolls and being provided with means for engaging and cleaning said chest extension by its reciprocatory motion, said doffer knife being provided with a guard spaced above it for directing the work along its course.

In testimony whereof I hereby affix my signature.

CHARLES E. WAREAM.

ciprocable longitudinally of the machine, and a doffer knife located between said intermediate rolls and chest for stripping the work from the intermediate rolls and being provided with means for engaging and cleaning said chest extension by its reciprocatory motion.

3. An ironing machine, comprising a reciprocating chest, a gang of padded rolls cooperating therewith, said chest having an end extension, work feeding means for delivering work to said chest extension, and a doffer knife for stripping work from the feeding means and arranged to cooperate with the chest extension for cleaning the same.

4. An ironing machine, comprising a reciprocating chest, a gang of padded rolls cooperating therewith, said chest having an end extension, work feeding means for delivering work to said chest extension, and a doffer knife for stripping work from the feeding means and having a pad on its lower face adapted to engage the chest extension and clean the same by the reciprocating motion thereof.

5. An ironing machine, comprising ironing means, a series of pressure rolls cooperating therewith, a movable pressure frame supporting said rolls and adapted by its movement to adjust the rolls as a gang toward and from the ironing means, gears on said rolls, driving gears for said roll gears, and zigzag linkage between said roll gears and driving gears for maintaining meshing relation thereof in all positions of said pressure frame.

6. A collar ironing machine, comprising preliminary polishing means including an initial set of lower ironing and upper pressure rolls and an intermediate set of rolls, drying means including a heated chest and a gang of upper feeding pressure rolls cooperating therewith and receiving the collars from said polishing means, movable pressure bar members supporting said gang of pressure rolls and extending beyond said intermediate preliminary rolls, and supporting the pressure rolls of said initial set, said chest having an end extension and being reciprocable longitudinally of the machine, and a doffer knife located between said intermediate rolls and chest for stripping the work from the intermediate rolls and being provided with means for engaging and cleaning said chest extension by its reciprocatory motion, said doffer knife being provided with a guard spaced above it for directing the work along its course.
